BANKING ENVELOPE

Harlan M. Whitman, Minneapolis, Minn., assignor to Curtis 1000, Incorporated, St. Paul, Minn., a corporation of Minnesota

Continuation of application Serial No. 573,687, March 25, 1956, now Patent No. 2,863,599, dated December 9, 1958. This application October 13, 1958, Serial No. 766,748

4 Claims. (Cl. 229—72)

This invention relates to envelopes and more particularly to envelopes for use by bank tellers and depositors at "drive-in" windows. Also the present envelopes are adapted for use by banks wherein the individuals are assigned deposit numbers and are given deposit identification cards.

An object of primary importance of the invention is to provide an envelope for temporarily retaining bills, coins, checks, etc. while they are being handed to a bank customer at a "drive-in" window by a bank teller and also while a deposit is being made by a customer at a "drive-in" window.

One feature of importance of the invention is that a special pocket is provided on the envelope in which the customer's identification card may be retained apart from the pocket and recess for coins, bills, checks, etc.

Another feature that is important is that the identification card pocket may be formed integrally with the envelope by folding a flap extending from the envelope panel opposite the end from which the coin pocket extends and gumming the free end of the flap to the inner face of the panel.

With the above and other objects in view, the invention may include the features of construction and operation set forth in the following specification and illustrated in the accompanying drawing.

In the accompanying drawing annexed hereto and forming a part of this specification, I have shown the invention embodied in an envelope especially designed for use by banks providing their depositors with deposit identification cards bearing a deposit number and identification of the depositor, the envelope having pockets extending partially over the inner face of the panel, a bill compartment or recess formed by a substantially triangular flap and a full length covering flap preferably forming a deposit slip, it being understood, however, that the invention can be otherwise embodied and that the drawing is not to be construed as defining or limiting the scope of the invention, the claims appended to this specification being relied upon for that purpose.

In the drawing:

Fig. 1 is a front elevation of a complete envelope made in accordance with the present invention with the covering flap shown in its closed position;

Fig. 2 is a similar view of the envelope shown in Fig. 1 with the covering flap open or unfolded; and

Fig. 3 is a view of the envelope blank prior to being gummed and folded.

In the above mentioned drawing there has been shown but one embodiment of the invention which is now deemed preferable, but it is to be understood that changes and modifications may be made within the scope of the appended claims without departing from the spirit of the invention.

This application forms a continuation of my co-pending application Ser. No. 573,687 filed March 25, 1956, now Patent No. 2,863,599 granted December 9, 1958. In addition to the coin pocket, bill recess and cover flap

2

shown and described in the above referred to application, the present envelope is provided with a supplemental pocket in which may be retained the depositor's identification card.

5 Referring more in detail to the figures of the drawing and first to Fig. 3, it will be seen that the blank from which the envelope is formed comprises a rectangular central panel 10 and flaps 12, 14, 18 and 22 extending respectively from each of its sides. From one long side 10 of the panel 10 extends the flap 12 preferably the full length of the panel 10 and of substantially the same width. This flap 12 may be suitably printed for use by the bank customer in making a deposit and may serve also to enclose the coin pocket and bill recess by having its lower edge tucked within the lower end of the bill recess presently to be described.

From the lower end of the central panel 10 extends a short flap 14 as shown having its transversely extending free end 16 gummed to the inner face of the panel at an intermediate portion thereof. From the upper end of the panel 10 extends a similar short flap 18 as shown having its transversely extending free end 20 gummed to the inner face of the panel 10. Preferably and as shown in the drawing the two flaps 14 and 18 are each curved 25 along their open side adjacent the edge of the panel 10 from which the covering flap 12 extends.

From the left hand side of the panel 10 as seen in Figs. 2 and 3 extends a substantially triangular flap 22 the lower end of which is provided with a small gummed extension flap 24 foldable inwardly and adapted to be gummed to the lower portion of the face of flap 14 forming the coin pocket. The upper portions of this flap 22 are cut away for convenience in counting bills while they are retained within the recess. Also the width of the lower portion of the flap 22 forming this bill receiving recess extends substantially the entire width of the panel 10.

In the use of this envelope the pocket for coins and the recess for bills, etc. formed by flaps 14 and 22 respectively are used as in the envelope shown and described in the above-referred to Letters Patent. The identification card pocket formed by the flap 18 provides a convenient receptacle into which the depositor may place his identification card when making a deposit.

45 As the inner side edges of the flaps 14 and 18 are closely adjacent the fold line between the panel 10 and flap 22 and are enclosed by the flap 22 they do not require gumming.

The lower edge of the bill recess formed by the flap 22 and gummed flap extension 24 is in substantial alignment with the lower edge of panel 10. The lower edge of the flap 12 may be and preferably is cut slightly above the lower edge of panel 10. By this means when coins or bills are retained in their pocket or recess the flap 12 may be tucked under the flap 22 to more securely retain the bills or coins within their recess or pocket.

55 I claim as my invention:

1. An envelope having a central panel, a substantially full length flap extending from one side of the panel, short flaps extending from opposite ends of said panel, and a substantially triangular flap extending from the side of the panel opposite said first flap, the flaps extending from the opposite ends of said panel being folded over the inner face of the central panel and having their transversely extending free ends gummed to the inner surface of said panel, said substantially triangular flap being gummed along its lower edge to one of said end flaps.

2. An envelope having a central panel, a substantially full length flap extending from one side of the panel, short flaps extending from opposite ends of said panel, and a substantially triangular flap extending from the

side of the panel opposite said first flap, the flaps extending from the opposite ends of said panel being folded over the inner face of the central panel and having their transversely extending free ends gummed to the inner surface of said panel, said substantially triangular flap having an extension flap inwardly folded and gummed to the inner face of one of said end flaps.

3. An envelope having a central rectangular panel and flaps extending from the opposite sides and ends thereof, the flaps extending from the opposite ends of said panel being substantially rectangular and having their transversely extending free ends gummed to an intermediate portion of said panel to form independent pockets, a generally triangular flap extending from a side edge of said panel and having one edge substantially coextensive therewith folded over said pockets gummed to the surface of one of said pockets, and a substantially full length generally rectangular flap extending from the side edge of the panel opposite said substantially triangular flap.

4. An envelope having a central rectangular panel and flaps extending from one end and the opposite sides thereof, the flap extending from an end of said panel being folded upon and having its transversely extending free end gummed to the inner face of said panel, a substantially triangular flap extending from a side of said panel and having one edge substantially co-extensive with the width of said panel and secured thereto, and a substantially full length rectangular flap extending from the side edge of said panel opposite said substantially triangular flap and foldable over said panel.
